UNITED STATES PATENT OFFICE.

JOSEPH MESSINA AND ANGELO C. MESSINA, OF PITTSBURGH, PENNSYLVANIA.

LOCK.

Application filed February 4, 1922. Serial No. 534,162.

To all whom it may concern:

Be it known that we, JOSEPH MESSINA and ANGELO C. MESSINA, citizens of the United States, residing at Pittsburgh, in the county 5 of Allegheny and State of Pennsylvania, have invented certain new and useful Improvements in Locks, of which the following is a specification.

This invention relates to a mortise lock 10 for doors, trunks, etc., and the primary objects of the invention are to provide a lock of such class, in a manner as hereinafter set forth, which requires a predetermined adjustment of the regulating hand to set the 15 tumbler to a particular position before the bolt can be thrown by the key, which includes a hinged cover plate having disguised latching means and that cannot be closed until the regulating hand has been shifted to 20 throw the tumbler from the adjusted position, and which permits of the removal of the key only after the locking operation.

Further objects of the invention are to produce a lock having a duplex locking bolt 25 actuated by means of a key after a predetermined adjustment of the tumbler, which is simple in its construction and arrangement, durable and efficient in its use, and comparatively inexpensive to manufacture.

With these and other objects in view, which will more fully appear as the nature 30 of the invention is better understood, the same consists in combination, arrangement and construction of parts hereinafter described, pointed out in the appended claims and illustrated in the accompanying drawing, it being understood that many changes 35 may be made in the size and proportion of the several parts and details of construction 40 within the scope of the appended claims without departing from the principle or sacrificing any of the advantages of the invention.

In the drawing forming a portion of this 45 specification and wherein like numerals of reference designate corresponding parts throughout the several views:—

Figure 1 is a front view of a lock in accordance with this invention, showing one 50 hasp and the cover plate in the open position.

Figure 2 is an end view of the casing cover and associated parts.

Figure 3 is a rear elevation of the casing cover with associated locking mechanism.

Figure 4 is an elevation showing the interior of the casing.

Referring in detail to the drawing 1 denotes a mortise lock casing mounted on one of the two relatively movable members to be locked together having anchored therein, as 60 at 2, a substantially V-shaped flat spring 3. One leg of the spring 3 abuts against the wall 4 of the casing, and the other against the top edge 5 of the duplex locking bolt 6, to be described. The casing 1 is further 65 provided with a centrally disposed boss 7 having an aperture adapted for threaded engagement with the screw 8 for securing the casing cover 9 to the casing 1 and for pivotally mounting the locking bolt 6 there- 70 between. A key spindle 10 is formed integral with the casing 1.

A pair of spaced hasps 11 and 12 mounted on the other of the relatively movable members is hinged connected, as at 13, to an 75 apertured securing plate 14. Each of the hasps 11 and 12 is provided on its inner face with a staple 15 adapted to extend through one of the slots 16 provided therefor, in the casing cover 9, and be engaged by respective 80 curved ends 17 and 18 of the locking bolt 6 when in the locked position.

The curved ends 17 and 18 of the locking bolt 6 extend in opposite directions relative to each other, providing, when the latter is 85 shifted to the locked position, the downward movement of the end 17 and the upward movement of the end 18, through respective staples 16 on the hasps 11 and 12. The bolt 90 6 is formed with a depending lug 19, adjacent to the curved end 17, and is adapted for engagement with the ward of the key during the locking operation.

A tumbler 20 is pivotally mounted, as at 21, in the lower portion of the casing cover 95 9, and is operated by a toggle mechanism 22 rigidly connected by a pin 23 to an indicator hand 24 pin 13 being journalled in the lock casing. A graduated scale 25 is formed on the outer face of the casing cover 9, by 100 which the hand 24 is set to operate the toggle mechanism 22 and shift the tumbler 20 relative to the shoulder 26 formed on the bolt 6 adjacent to the end 18, and permit of the operation of the bolt 6 by the key.

The tumbler 20, toggle mechanism 22 and locking bolt 6, are all mounted on the inner face of the casing cover 9. The toggle mechanism 22 is pivotally connected, as at 27, to the tumbler 20. By varying the connection 110 of the indicator hand 24, on the outer face of the casing cover 9, with the toggle mech-

anism 22, the indicator hand 24 must be shifted to a predetermined point on the graduated scale 25 before the tumbler 20 is properly positioned relative to the shoulder 26 to permit of the shifting of the bolt 6 to the unlocked position. A knowledge of the indicator hand adjustment is therefore required before the bolt 6 can be shifted by the key. Different keys may also be employed by shaping the wards thereof to fit projecting ridges, as indicated at 10' in its path of travel permitting only the operation of a key having corresponding notches.

A cover plate 28 is hinged to the lower portion of the casing cover 9 and is provided with a staple 29 adapted to be engaged by the latch 30 through the slot 31 in the upper portion of the casing 9. A flat spring 32 is mounted on the inner face of the cover plate 28 and is provided for the purpose of throwing the latter to the open position when the latch 30 is released. The inner face of the plate 28 is further provided with a transverse groove 33 to clear the indicator hand 24 when the plate 28 is in the closed position. The position of the groove 33 in the plate 28 is such that the indicator hand 24 must be shifted from the adjusted position before the plate 28 can be closed. By this arrangement the indicator hand 24 can never be inadvertently left in the adjusted position, thereby preventing its operation by an unauthorized person even if provided with the key.

The latch 30 is shiftably mounted in a pair of spaced aperture lugs 34 and carries a coil spring 35 mounted therebetween. The action of the spring 35 normally holds the latch 30 in the latched position. The latch 30 is provided with an actuating arm 36 laterally slideable in a groove 37 formed in a corner of the casing 1 in the wall 4. The construction of the arm 36 is such that when in the latched position it ostensibly forms a portion of the wall 4 which is not readily detected by one not acquainted with its construction.

Besides assuring the positioning of the indicator hand 24 from the adjusted position, as above stated, the closure of the cover plate 28 also provides for the concealment of the key hole 38, and for the protection of the indicator hand 24 and scale 25.

The bolt 6 is formed with an angularly disposed edge 39 which abuts against the pin 23 to limit the movement of the bolt when shifted to the unlocked position, and a stud 40 is fixed in the casing 1 to engage the

curved end 17 of the bolt 6 to limit its movement when shifted to the locked position.

When the bolt 6 is thrown into the unlocked position by the key, the latter will hold the bolt in such position and cannot be removed from the lock until the key is returned to permit of its removal from the key hole 38. Upon such return movement of the key, however, the action of the spring 3 in engagement with the edge 5 of the bolt 6, will automatically shift the bolt to the locked position.

The wall 4 of the casing 1 is provided at each side, thereof with a laterally projecting apertured ear 41 by which the casing 1 and associated parts carried thereby are secured in position.

What we claim is—

1. A lock comprising a casing, a locking bolt therein and shiftable to and from locking position, said bolt having oppositely disposed ends, a tumbler controlling the movement of the bolt, hasp elements adapted to extend into the casing and engaged and locked by said ends when the latter are shifted to locking position, means for adjusting the tumbler to permit of the shifting of the bolt to release the hasp elements, an indicator device associated with said means, and a cover plate for the indicator device including means for permitting said cover plate only when the tumbler has been shifted to a determined position.

2. A lock comprising a pivoted locking element, shiftable to and from locking position, means engaged by said element for locking an object therewith, a tumbler controlling the movement of said element, an adjusting device for said tumbler to permit of the shifting of said element to release said means, and an indicator element for said adjusting device.

3. A lock comprising a pivoted locking element, shiftable to and from locking position, means engaged by said element for locking an object therewith, a tumbler controlling the movement of said element, an adjusting device for said tumbler to permit of the shifting of said element to release said means, and an indicator element for said adjusting device, and a releasable element for concealing said indicator element.

In testimony whereof we affix our signatures.

JOSEPH MESSINA.
ANGELO C. MESSINA.
